UNITED STATES PATENT OFFICE.

HARRY F. MORRIS AND RITNER SHINN, OF COLLINGSWOOD, NEW JERSEY.

FORCED-DRAFT WATER-GRAVE.

1,261,268.

Specification of Letters Patent. Patented Apr. 2, 1918.

Application filed September 14, 1917. Serial No. 191,361.

To all whom it may concern:

Be it known that we, HARRY F. MORRIS and RITNER SHINN, citizens of the United States, residing at Collingswood, in the 5 county of Camden and State of New Jersey, have invented certain new and useful Improvements in Forced-Draft Water-Grates, of which the following is a specification.

Our invention relates to improvements in 10 water grates used in connection with forced draft.

An object of our invention is to provide means, in a grate of the class described, to admit the proper amount of air to said 15 grate to obtain a more perfect combustion of fuel under a given pressure.

A further object is to provide an interchangeable disk, in connection with said grate, whereby the volume of air to be admitted to the grate may be regulated, as desired, in accordance with the pressure, without removing or changing the grate.

A further object is to provide means, connected with said grate, to prevent a back 25 draft of gases thereby avoiding the danger of an explosion.

A further object is to provide means to prevent sediment settling in the air chamber and the elimination of an ash pan.

30 We attain these and other objects by means of the mechanism illustrated in the accompanying drawings, wherein,

Figure 1 is a plan view of the device;

Fig. 2 is a sectional view of the device on 35 line 1—1 of Fig. 1;

Fig. 3 is a plan view of the disk used to regulate and vary the amount of air to be admitted to the grate, three separate disks being shown, illustrating variations in the 40 size and number of openings therein;

Fig. 4 is a sectional view of a disk illustrating the locking mechanism, and

Fig. 5 is a sectional view of the ball plate showing the opening therein with the ball 45 seated.

Similar reference characters refer to similar parts throughout the drawings.

Referring to the drawings a fire grate *a* is provided at the front with a water inlet 50 pipe *h* whereby water *s* enters and circulates through said grate *a*. A water outlet pipe *i* is provided at the back of said grate *a* whereby the water after circulating through said grate, and being subjected to the heat 55 therein, is carried off, thus providing a continuous circulation of water through said

grate. This will prevent the grate becoming overheated thereby burning out or melting the same. The fire grates now in use burn out and melt very rapidly under a 60 high, continuous fire.

The said grate *a* is provided with cored holes *o*, having the recesses *p* to engage the ears or lugs *f* on disks *c*, so that said disks *c* may be securely held in position.

65 An air chamber *b* is provided, having the door *k* for access thereto and a latch *l* to secure same in a closed position. This door *k*, however, may be secured by means of a bolt, or other suitable means as will insure, 70 as near as possible, an air tight connection.

To obtain forced draft air is forced, by a blower, or any suitable means, through the pipe *j* into and through the air chamber *b* as indicated by the arrows. Said air chamber *b* has cast integral therewith the lip *m* upon which rests the ball plate *r*. This ball plate *r* is made of steel, or other suitable heat resisting material, and is provided with the openings *e*, the upper part of said openings *e* being ground out to form a socket for the ball *d* to seat. These openings *e* correspond with the cored holes *o* in the grate and communicate with the air chamber *b*. The ball *d* is constructed of steel, or other suitable heat resisting material, and of a size and weight suitable for the purpose hereinafter set forth.

80 The disks *c* are provided with an opening or openings *g*, as illustrated, and have integral therewith, the ears or lugs *f* to engage in recesses *p* in the grate *a*.

In operative position the grate *a* rests upon the ball plate *r* which in turn rests upon the lip *m* of the air chamber *b*. The 95 balls *d* rest in the sockets ground in the upper part of the openings *e* of said ball plate *r*. The disks *c* are then placed over the cored holes *o* in the grate *a* and are turned until the lugs thereon engage with the recesses *p*, as before stated, securely holding the disks in position. Air is then forced into the air chamber *b*, in the manner hereinbefore set forth. This will force the ball *d* slightly from its seat in the socket aforesaid 100 and to one side thereof, thereby permitting the air to enter and circulate through the cored holes *o* of the grate *a*.

105 The amount of air to be admitted to the grate will determine the area of the openings in the disks to be placed in operative position. The greater the pressure the less

the area of the said openings. Therefore, to increase the pressure of the forced air decrease the area of the openings in the said disks and, *per contra*, to decrease the pressure increase the area of said openings. This is accomplished by placing in operative position in the cored holes *o* in said grate, disks *c* having a greater or less number of openings therein of a larger or smaller circumference.

We find in practice that it requires about 250 cubic feet of air to burn a pound of fuel and that it takes about one minute for one cubic foot of air to pass through a one-eighth inch opening under one ounce of pressure. So to burn a given amount of fuel, within a given time, securing the maximum of heat therefrom, we force sufficient air into the cored holes *o* of the grate and then by placing disks *c* in operative position thereon with an opening or openings in said disks of sufficient area to admit the amount of air requisite to the grate, we obtain the proper combustion of fuel to attain the result desired.

It is necessary to use uniform disks throughout in order to obtain the same pressure over the entire surface of the grate.

The disks *c*, being interchangeable, can be easily removed by means inserted in the openings therein, and other disks inserted without, of course, changing or removing the grate.

As before said, when the draft is on, the ball *d* will be forced slightly from its seat in the socket provided in the openings *e* thereby permitting the air to pass into and circulate in the cored holes *o*. When the draft is off, the ball *d* reseats in the socket aforesaid. In this way we prevent any sediment from passing through into the air chamber *b*, because when the draft is on no sediment can drop down, it being forced back on the fire and when the draft is off, and the ball seated, the opening into the air chamber is closed.

From our use of the device we find that we do not have any sediment and that we consume practically all of the carbon and heat producing elements of the fuel used. Again when the draft is off, and the ball seated, there can be no back draft of gases, which prevents explosions.

With this device, we find that we can use to advantage the cheaper grades of fuel, such as bird's eye, buckwheat and coal dust, turf, peat and the like as well as the higher grades of fuel.

From the foregoing description taken in connection with the accompanying drawings, the advantage of the construction and of the method of operation will be readily apparent to those skilled in the art to which the invention appertains, and while we have described the principle of operation of the

invention, together with the device which we now consider to be the best embodiment thereof, we desire to have it understood that the device shown is merely illustrative, and that such changes may be made therein, when desired, as are within the scope of our invention.

Having thus described our invention what we claim as new and desire to secure by Letters Patent is:

1. In combination with a water grate, having a continuous circulation of water therethrough and having cored openings therein, of an air chamber, means for admitting air to said chamber, a plate secured between said air chamber and said grate having openings therein to correspond with the openings in said grate and communicating with said air chamber whereby air is admitted to said grate, a ball, the openings in said plate being ground in the upper portion thereof to form a socket in which the ball normally seats and means to be secured in the openings in said grate to regulate the amount of air to be admitted to the grate, substantially as shown and described.

2. In combination with a water grate, having a continuous circulation of water therethrough and having cored holes therein, of an air chamber, a plate secured between said air chamber and said grate having openings therein to correspond with the openings in said grate and communicating with said air chamber, a ball, said plate openings being ground in the upper portion thereof to form a socket in which the ball normally seats, thereby providing means to prevent sediment settling in the air chamber and eliminating the necessity of an ash pan, substantially as shown and described.

3. In combination with a water grate, having a continuous circulation of water therethrough and having cored openings therein, of an air chamber, a plate secured between said air chamber and said grate having openings therein to correspond with the openings in said grate and communicating with said air chamber, a ball, the openings in said plate being ground in the upper portion thereof to form a socket in which the ball normally rests, means for admitting air to said chamber whereby the ball is unseated, permitting the admission and circulation of said air through the openings in said grate, substantially as shown and described.

4. In combination with a water grate, having a continuous circulation of water therethrough and having cored openings therein, of an air chamber, means for admitting air to said chamber, a plate secured between said air chamber and said grate having openings therein to correspond with the openings in said grate and communicating with said air chamber whereby air is ad-

mitted to said grate, a ball, means to seat said ball in the openings in said plate, interchangeable disks, means for securing said disks in the openings in said grate, said 5 disks having openings therein of sufficient area to admit the amount of air to said grate requisite, in connection with the pressure of the forced draft, to obtain the proper combustion of fuel.

10 5. In combination with a water grate, having a continuous circulation of water therethrough and having openings therein, of an air chamber, means for admitting air to said chamber, a plate secured between said 15 air chamber and said grate having openings therein to correspond with the openings in

said grate and communicating with said air chamber, whereby air is admitted to said grate, a ball, the openings in said plate being ground in the upper portion thereof to form 20 a socket in which the ball normally seats, thus providing means for the prevention of the back draft of gases when the draft is off and the ball seated, substantially as shown and described. 25

In testimony whereof we affix our signatures in the presence of two witnesses.

HARRY F. MORRIS.
RITNER SHINN.
